(21) Appl. No.: 29/293,712

(57) CLAIM

(22) Filed: Dec. 7, 2007

I claim the ornamental design for a combined smoking article holder, towel holder and club lean, as shown and described.

(51) LOC (9) Cl. 27-06

DESCRIPTION

(52) U.S. Cl. D27/183; D21/796

FIG. 1 is a perspective view showing my design for a combined smoking article holder, towel holder and club lean in a folded position with the towel holder in a retracted state.

(58) Field of Classification Search D27/172,

FIG. 2 is a side view of FIG. 1.

D27/187, 183; 131/259; 473/282; D21/796

FIG. 3 is a back view of FIG. 1.

See application file for complete search history.

FIG. 4 is a perspective view showing my design in an assembled position with the towel holder in an extended state; and,

FIG. 5 is a top view of FIG. 1.
